BREAST PUMP

Filed Sept. 18, 1929

INVENTOR:

Erik Lindqvist

UNITED STATES PATENT OFFICE

ERIK LINDQVIST, OF MALMO, SWEDEN

BREAST PUMP

Application filed September 18, 1929, Serial No. 393,541, and in Sweden July 12, 1928.

The present invention relates to an auxiliary device for the suckling of babies which is to be used in the first time after delivering of a child if the suction power of the child is too little or the nipples have to be protected against inflammation.

A form of execution is shown in the accompanying drawings by way of example:—

Fig. 1 is a side view of the suction bell of the device which has to be put over the nipple.

Fig. 2 shows the proper suction device also in side view.

The device according to the invention consists of a part 1, called the suction bell, which is to be put over the nipple of a woman lately confined and of the proper suction part 2, both parts being connected by a tube 3 of flexible material for instance india rubber.

This part 1 consisting of transparent glass, is put in known manner with its large flat edge 4 over the nipple, so that by the effect of the suction exerted on the mouth piece 5 of the suction device by the woman lately confined the nipple is sucked in the suction bell. Hereby the flat part 4 is pressed on the surrounding parts of the nipple and in this manner the milk vessels are emptied.

The other part of the suction bell 1 consists of a short wide tube 6 inclined in an angle of 45° with respect to the plane a—b. Over this flanged socket 6 the sucking tube and tip of india rubber is pulled over and kept in its position by an enlargement 6a. On the other part 7 of the suction bell the flexible tube 3 is arranged and kept also in its position by an enlargement 7a.

On the other end of the flexible tube 3 the proper suction device is arranged, which consists also of glass. The tube of india rubber is pulled over the enlargement 9a of a glass tube 9 which is enlarged at its end as shown by 10 in Fig. 2. On the other end of the enlarged part 10 an obliquely directed tube 5 is fixed which forms the mouth piece. In the interior of the enlarged part 10 a short tube 11 of small diameter is arranged which communicates with the tube 9 and which is provided with an opening 12 at the upper end. In the short tube 11 a valve 13 consist-

ing of a short piece of glass is provided which forms the suction valve. The lower end of this glass valve is pointed and fits into the lower part of the short tube 11. In order to limit the upward movement of the valve 12, several little projections 14 are arranged.

If a suction effect is exerted at the mouth piece the suction valve is lifted whereby the milk is sucked out of the nipple. The main object of the arrangement of the enlarged part 10 which is not in communication with the flexible tube and of the short tube connected with the flexible tube having an opening at the upper end is to prevent the mixture of the spittle with the milk, an inconvenience which is avoided by the present invention.

It is understood that the device may be of any other suitable material, which is not transparent, but care must be taken that the suction device with the spittle collector and the arrangement of the suction valve must be as described in the description.

In case that a woman lately confined is unable to exert a suction effect on the mouth piece, a ball of india rubber provided with a valve may be arranged and fixed on the tube 7.

I claim:—

1. A breast pump comprising in combination a suction chamber formed with a bell shaped mouth and two tubular extensions of different diameters, a nipple fitted on to the larger tube, a glass container with a tubular extension, a glass tube concentrically arranged within said container and projecting out a short distance therefrom, a flexible tube connected to the tube extending from the container and to the small tube of the suction chamber and a glass non-return valve provided in the tube within the glass container.

2. A breast pump comprising in combination a glass suction chamber formed with a bell shaped mouth and two tubular extensions, a nipple fitted on to one tube, a glass container formed with a mouth-piece, a glass tube concentrically arranged within said container and extending therefrom, a flexible tube connecting together the suction chamber and container being fitted on to the re-

spective tubes, a valve seating formed in said glass tube within the container, a glass valve co-operating therewith, said tube constricted at the end limiting the movement of said valve and eliminating saliva passing there-through.

In testimony whereof I affix my signature.

ERIK LINDQVIST.
